UNITED STATES PATENT OFFICE.

JOSEPH M. SHUTE AND LORENZO M. SHUTE, OF PHILADELPHIA, PA.

EXCAVATING APPARATUS.

SPECIFICATION forming part of Letters Patent No. 290,488, dated December 18, 1883.

Application filed March 31, 1883. (No model.)

To all whom it may concern:

Be it known that we, JOSEPH M. SHUTE and LORENZO M. SHUTE, citizens of the United States, residing at Philadelphia, in the county 5 of Philadelphia and State of Pennsylvania, have jointly invented certain new and useful Improvements in Excavating Apparatus; and we do hereby declare the following to be a full, 10 clear, and exact description of the invention, reference being had to the accompanying drawings, which form part of this specification, in which—

Figure 1 is a side elevation of our improved excavating apparatus. Fig. 2 is a plan view 15 of the same. Fig. 3 is a vertical transverse section. Fig. 4 is a vertical longitudinal section, and Fig. 5 a plan view of the rope supporting supplementary truck. Fig. 6 is a vertical longitudinal section of the upper portion 20 of the rear end of the apparatus, with two of the trucks in position. Figs. 7 and 8 are side views, and Fig. 9 a bottom view, of one of the buckets.

Our invention has reference to that method 25 of excavating in which the excavated material, instead of being thrown up to one side of and then thrown back again into a trench or other excavation, is carried up and back and deposited at once in the part of the trench 30 where filling is needed.

Our invention has reference to the apparatus whereby the method or process is carried on; and our improvements consist in the peculiar construction and combinations of parts 35 hereinafter fully set forth.

In carrying our invention into effect, we 40 erect on the street or thoroughfare in which the trench is to be made, and in line with such proposed trench, a trestle-work or framing of timber, forming the support for a railway-track laid thereon. On this track we place a number of cars, and to each car we attach a draft rope or cable. These draft ropes or cables are carried along to and are connected with a main 45 cable, which proceeds to the other end of the trestle or framing, passing over a pulley or roller there located, and extending to a winding-drum connected with an engine. When this drum is rotated in one direction, the cars 50 will be drawn toward one end of the framing or railway, said cars, when the direction of rotation of the drum is reversed, being drawn

backward on the railway by another cable. A latch, which is automatically tripped, holds the last car at the starting end of the framing until said latch is lifted. The draft-rope of each car passes around pulleys located beneath such cars, buckets being hung on said pulleys. These buckets are designed to receive the excavated material, being lowered to the ground 60 or into the trench for that purpose. When filled, draft is applied to the main cable, and thence to the draw-ropes of said cars. This first raises the buckets by taking up the slack of the ropes, and, after such buckets are raised, 65 automatically latches them on the cars, and causes them and said cars to be moved lengthwise of the trestle-work until they reach the upper or opposite end of the latter. Said buckets have self-opening or hinged bottoms, 70 which are released and lowered by contact with stops on the frame-work, allowing the contents of said buckets to drop out. Said bottoms are counterbalanced by weights, and are provided with latches, so that as soon as the 75 buckets are emptied the bottoms close and fasten, after which such buckets are returned to be filled again. An indicator with bell is provided to register and signal as each trip is made by the cars and buckets. 80

Referring to the accompanying drawings, A indicates a trestle-work or framing erected over the line of a proposed trench or other excavation. Said trestle-work or framing consists, essentially, of the uprights B B, which 85 arise from the base-pieces C C, the latter having rollers c c, to facilitate the movement of the structure as the excavation proceeds. The structure, if desired, is made in beats or sections D D, which said beats or sections are rigidly 90 and firmly secured to one another, to form a steady and substantial support for a railway and for the cars thereon. The uprights are suitably braced and stayed, as shown, and are placed in two ranks, so as to leave a clear 95 opening lengthwise between them.

E E are timbers projecting inwardly from the uprights B B, and arranged to support a track, E' E', (on which metal rails may be laid,) extending from one end of the trestle-work to 100 the other. The space between the timbers or tracks E E is open and unobstructed.

I I I I show cars or trucks adapted to run on the tracks E E. To these cars are attached

- draft-ropes *i i i i*, their opposite ends being spliced or connected at K, from which point extends a main cable, *k*, that passes over a pulley or roller, *k'*, and winds upon a drum, *l*, which is caused to revolve by an engine. Each of the ropes *i*, &c., passes beneath the car, to which it is fastened, and under a pulley, *m*, to the block of which is attached a bucket, *M*. When slack is allowed to a rope, its bucket is lowered.
- 10 When such slack is taken up, the tub is raised. Each bucket has a bottom, *m'*, hinged at *m''*, and provided with two counterbalance-weights, *m''*, whose gravity is sufficient to close said bottom when relieved by discharging its contents.
- 15 Latches *m''* are also provided, which lock said bottoms when closed, and keep them locked until said latches are opened by contact with studs *b b*, projecting laterally from the timbers B B. Such contact occurs when said buckets 20 are moved backwardly to their respective discharging-points, as hereinafter explained.
- N represents a latch consisting of two levers, *n*, with heads *n'* at the forward or starting end of the trestle-work, which engages with 25 the end car when it reaches that point. This latch holds said car, so that after the buckets are filled draft on the main cable will elevate said buckets by taking up the slack in the draft-ropes before starting the cars.
- 30 O represents a wire extending along the framing, and connected at one end with a spring stud or lever, *O'*, and at the other end with the hammer of a bell, *O''*. At every trip the car I meets and presses against the stud *O'*, causing the bell to ring, thereby giving notice to the engineer of the completion of the backward run. A dial-register, P, is also connected with and actuated by the same means, so that a record of the number of trips accomplished 35 is thus made.
- We do not deem it necessary to illustrate or particularly describe the detail mechanism of the dial-register and bell, as any of the well-known expedients employed where a dial-register or bell is serviceable may be used.
- 40 On the track-timbers E E a car or truck, Q, is placed to support the draft-ropes and main cable, and to prevent sagging of said ropes and cable. This truck runs on rollers or wheels, 45 and has a vertically-moving clamp, Q', consisting of a cross-piece, *q*, below the sills or frame, and a vertical standard, *q'*, connected thereto and passing through the frame. A spring, *q''*, normally tends to raise the clamp and bind 50 the draft-ropes between the cross-piece *q* and the frame of the truck. A lever or incline, *q''*, is connected to this spring, as shown, so that when truck Q reaches the end of the framing said lever will be depressed in passing under a cross-bar, W, on the frame, and thus compress the spring *q''*, releasing the draft-ropes 55 from the clamp, so they may be wound on a drum, and thus draw the train of cars clear up to the end of the frame A.
- 60 Depending from the truck Q are studs or pins *q''*, which pass down between the draft-ropes, so that when the cars are drawn back-

wardly by the cable said pins will be engaged by the splice K, thus drawing the truck from beneath the cross-bar, and permitting the clamp Q to again press the draft-ropes and bind the truck Q thereto, so as to cause said truck to travel with said ropes and prevent their sagging.

Depending from each car is a device for 75 hooking the buckets thereto. Said device consists of a rigid hanger, R, having a bent or flaring lower end, *r*, and a pivoted curved latch, *R'*, having a shouldered head, *r'*. The straps *m''* of the pulleys *m* have each a cross-bar, *m''*, and when the buckets M and said pulleys are raised by draft on the cable and draft-ropes said cross-bars pass in between the hangers R and latches *R'* and engage with the shouldered heads of the latter.

S represents a slide secured to the end of the rear car, above the head of the catch. When the buckets are raised, the cross-bar *m''* of the pulley *m* belonging to the rear car strikes and raises said catch, relieving said car from engagement therewith, and permitting the train of cars to be drawn along the track. When said cars return to their normal position, after the buckets have been dumped, the catch automatically re-engages with the end car, as before, and holds the train in position until said catch is again lifted, as described. One of the cars of the train—preferably the one next to the last or rear car—has a frame-piece or buffer, T, united to the body of the car through the medium of an elliptical spring, *t*. When the cars return to normal position, this buffer meets a rigid block, *t'*, attached to the frame of the structure, (see Fig. 6,) so that said spring is compressed and the buffer T moved 100 toward the body of the car, or the latter moved toward the buffer.

U represents a bar or connecting-rod secured to and operated by buffer T, to which the upper ends of the latches *R'* are attached, 110 whereby a longitudinal motion of said rod in one direction will cause said latches to swing away from the hangers R, releasing the buckets, an opposite motion of said rod moving the said latches toward the said hangers. 115 When the cars return, as just suggested, and the spring *t* is compressed, a longitudinal motion is communicated to the rod U, causing the latches *R'* to swing away from the hangers R, thus releasing the buckets and allowing 120 them to descend into the excavation where they are to be filled. The buckets thus are all lowered simultaneously to be filled, and it is desired that they should also be dumped simultaneously. We prefer, also, that the dump 125 should occur on the backward rather than on the forward motion of the cars, and to this end the forward sides of the bucket-latches and the rear sides of the stops on the framing are rounded, their opposite side being straight. 130 On the forward motion of the cars the buckets will swing without opening in passing the stops, while on the backward motion their latches will open, releasing their bottoms,

which drop down, discharging their contents. As soon as the dump is accomplished the counter-balances raise the bottoms of the buckets and automatically relatch them, the latches 5 sliding up over the inclines of the keepers and catching on the shoulders. The cars then continue their backward motion to the point from which they first started. When they reach this point, a hanger on one of the cars strikes 10 a pivoted bell-lever, producing draft on a bell-wire, and causing a bell or gong to be struck, thus notifying the engineer, who thereupon suspends draft on the cable. The buckets or tubs then, in the manner already described, 15 are automatically unlatched, and by their gravity descend into the trench, where they are filled. As soon as filled notice is sent to the engineer by a pull on the bell-wire, whereupon the engine is again started and the buckets 20 lifted as before.

The operation is substantially as follows: The buckets, being lowered into the trench or excavation, are then filled. A signal being sent to the engineer, the latter starts the engine, 25 causing the main cable to be wound upon the drum and draft and applied to the ropes. This elevates the buckets out of the trench, and raises them until their pulleys automatically engage with the latches. The latches or brakes 30 are also lifted automatically, and, the draft being continued, the cars are drawn along the railway until the train reaches the upper end of the framing. The motion of the engine is now reversed, the cable drawing the train 35 backward, the tubs being all simultaneously dumped as they pass the stops. The backward motion of the train continues until the cars reach their first position over the excavation, when the train comes to a state of rest, 40 the end car automatically engaging with the catches, and the buckets being released from the catches and lowered into the excavation. As the excavation proceeds, the trestle-work may from time to time be drawn or advanced along 45 the line of the trench-opening.

By the construction and arrangement herein described it will be noted that the entire apparatus may be worked by the engineer or party in charge of the engine, the lifting of 50 the tubs, the movement of the same with the car, the discharge of the contents, the close of the bottoms of the tubs, their return and lowering requiring no direct attendance or help.

The whole force therefore required for working our apparatus is an engineer and workmen for filling the buckets. This, it will be seen, is a great advantage over a system involving the employment of attendants to raise, lower, and dump the tubs. 55

Instead of buckets, baskets, grappling-hooks, 60 or other equivalent device may be used.

What we claim as our invention is as follows:

1. The combination, with a series of trucks, I I, provided with latches R R', of the connecting rod or rods U, the buffer T, attached to one of said trucks and connected with the rod U, and the stop t', substantially as described. 65

2. In combination with the trestle-work or framing and cars supported and running thereon, the wire connected, substantially as described, at one end with a stud or lever, and at the other end with a bell, substantially as and for the purpose set forth. 75

3. In combination with the trestle-work or framing and cars supported thereon, the wire O and an indicator or register for noting trips, substantially as set forth. 75

4. In an excavating apparatus comprising 80 a trestle or elevated railway, a train of cars or trucks drawn thereon, and buckets suspended from and supported by said cars or trucks, the combination, with the bucket supporting and conveying truck, of an independent cable for 85 each truck and its bucket, and a supplemental truck constructed and adapted to prevent sagging of the cables, substantially as described.

5. The supplementary truck Q, provided with a cable-gripping device or clamp, in combination with devices for automatically actuating said clamp to cause it to grasp or release the cables, substantially as shown and described. 90

6. The rope or cable holding clamp, in combination with the bucket-cable and the car or truck, substantially as described and shown. 95

In testimony that we claim the foregoing we have hereunto set our hands this 29th day of March, 1883.

JOSEPH M. SHUTE.
LORENZO M. SHUTE.
